LIGATURE PACKAGE

Edward Themak, New York, N. Y., assignor to
Geck Laboratories, Inc., New York, N. Y., a
corporation of New York

Application January 5, 1935, Serial No. 535

7 Claims. (Cl. 206—63.3)

The present invention has for an object to provide an improved package for gut ligature.

Surgical ligatures are supplied to physicians and surgeons each in a compact package comprising an hermetically sealed frangible glass vial containing a ligature together with a preservative liquid.

The ligature package of this invention is an improvement on the package shown in Patent No. 1,887,529 granted to me November 15, 1932, in that the gut ligature is so wound on a suitable holder that it is better preserved. The ligature of the package shown in said patent is wound in long loops about the holder and, therefore, has portions that are substantially straight and other portions that are bent on a relatively short radius. When this ligature is removed and straightened out, the bent portions are less strong than the straighter portions and, also, they are slightly rough due to an unevenness in the twist. In the present package the ligature is wound in a helical coil in such a way that the curvature of the ligature is the same throughout its length. Furthermore, the ligature is more quickly and easily removed from the holder and with less chance of snarling while the advantages of the projecting tab carrying size and quality marks as provided by the holder of the patent is retained. These new advantages are provided by forming the ligature in a helix about a straight holder from which it can be readily pulled for use.

The nature and objects of the invention will be better understood from a description of a particular embodiment thereof for the purpose of which description reference should be had to the accompanying drawing forming a part thereof and in which—

Figure 1 is a view in side elevation of a ligature package embodying the invention.

Fig. 2 is a perspective view of a ligature holder of the type shown in the package of Fig. 1 showing the ligature in process of being removed from the holder.

Fig. 3 is a detail view showing a ligature having right hand helical lines indicating the twist formed in a right hand helical coil, and Fig. 4 is an end view of the thin strip and the helical ligature wound thereon.

In the arrangement shown for the purposes of illustration the ligature 5 on a holder 6 is enclosed in a frangible glass vial 7 with a preservative liquid. The holder is a long narrow thin flat strip of suitable fibre board or other suitable material, the ligature is in the form of a cylindrical helix fitting not too tightly on the

holder 6. The ligature should not be wound tightly enough to cause a sharper bend or break over the edges of the holder. The holder is provided with spaced apertures 8, 9 as securing devices to receive and retain the ends of the ligature and between which the coil lies. Beyond the coil position a projecting tab 10 is provided which may receive the designations indicating the style, size, quality, etc. of the ligature. The aperture 8 is preferably formed as an open ended longitudinal slot such that the ligature can readily be removed from the holder without inconvenience or delay when the package is opened. The second aperture 9 is preferably in the form of a longitudinal slot rather than a round hole, so that the end of the ligature can be easily pulled therefrom and will not catch in the hole as the ligature is removed.

As shown in Fig. 2, the ligature may be removed from the holder as a whole after which it is straightened by direct pull on the opposite ends. The direction of the turn of the coil is the same as the direction of the twist of the ligature, whereby as the ligature is pulled straight after removal from the holder the twist of the ligature will be increased rather than decreased. Whether the direction of the turn of the coil and the twist of the ligature are the same as in Fig. 3 or different, the increase or decrease of twist will be uniform throughout the length of the ligature. The arrangement whereby the twist is increased upon straightening of the ligature is preferred because it is better to originally provide a lesser twist and then increase it upon removal than to provide a greater original twist and decrease it later. The term "direction of twist" as here used refers to the direction of the helical lines formed by the twist.

There are certain definite advantages in the particular form of holder shown but obviously the form may be varied while retaining some of the advantages. For example, a holder which is cylindrical and fits tightly, or preferably loosely, within the helix will still preserve the ligature and will permit it to be removed quite readily.

The foregoing particular description is illustrative merely and is not intended as defining the limits of the invention.

I claim:

1. A ligature package comprising a hermetically sealed vial and enclosed therein a surgical gut ligature with a holder on which said ligature is wound comprising a long narrow thin flat strip, the gut ligature forming a helical coil circular in cross section about said holder, said holder hav-

ing means for engaging the ends of the ligature to prevent accidental unwinding of the coil.

2. A ligature package comprising a hermetically sealed vial and enclosed therein a surgical gut ligature with a holder on which said ligature is wound comprising a long narrow thin flat strip, the gut ligature forming a helical coil circular in cross section about said holder, said holder having means for engaging the ends of the ligature to prevent accidental unwinding of the coil.

3. A ligature package comprising a hermetically sealed vial and enclosed therein a surgical gut ligature with a holder on which said ligature is wound comprising a thin flat straight sided strip having spaced ligature receiving apertures to receive and retain the ends of the ligature wound therebetween and a data tab extending beyond one of said apertures, the ligature forming a helical coil circular in cross section about said holder between the apertures with its ends projecting through the apertures.

4. A ligature package, as defined in claim 3, wherein the wind of the coil is of the same direction as the twist of the ligature whereby when the ligature is drawn from the holder by one end the twist of the ligature is tightened.

5. A ligature package comprising a hermetically sealed vial and enclosed therein a long straight sided thin flat holder having spaced ligature securing devices, a ligature wound about said holder

between said devices to form a helical coil circular in cross section with its ends secured by said securing devices to prevent accidental unwinding thereof, one of said securing devices consisting of a slot open at one end of the holder whereby the coiled ligature can be removed by merely stripping it bodily from the holder, substantially as described.

6. A ligature package comprising a hermetically sealed vial and enclosed therein a surgical gut ligature with a holder on which said ligature is wound comprising a long narrow thin flat strip, the gut ligature forming a helical coil circular in cross section about said holder, said holder having one end projecting beyond the coil to provide a data carrying tab.

7. A ligature package comprising an hermetically sealed vial 7, and enclosed therein a helical gut ligature with a holder 6 on which said ligature is wound in a helical coil circular in cross section, said holder comprising a straight sided thin flat strip having spaced ligature receiving apertures 8 and 9 to receive and retain the ends of the ligature wound therebetween, one aperture, 8, being open at the end of the holder whereby the coiled ligature can be removed by merely stripping it bodily from the holder, substantially as described.

EDWARD THEMAK. 30
